UNITED STATES PATENT OFFICE.

HANS PETERSEN, OF MINNEAPOLIS, MINNESOTA.

LINOTYPE-MACHINE.

No. 888,649.

Specification of Letters Patent.

Patented May 26, 1908.

Application filed August 26, 1907. Serial No. 390,094.

To all whom it may concern:

Be it known that I, HANS PETERSEN, a citizen of the United States, residing at Minneapolis, in the county of Hennepin and State 5 of Minnesota, have invented certain new and useful Improvements in Linotype-Machines; and I do hereby declare the following to be a full, clear, and exact description of the invention, such as will enable others skilled in the 10 art to which it appertains to make and use the same.

This invention relates to so-called linotype machines, wherein matrices are released, one at a time, from a magazine by means of escapement devices, and are delivered through 15 guide channels to the casting mechanism where the linotype or slug is cast from the assembled line of matrices, and the said matrices are subsequently returned to the magazine by a suitable distributing mechanism.

In practice, it has been found that certain letters of the alphabet are used much more frequently than others, and, hence, that a very much larger number of matrices bearing 25 these frequently used letters must be employed than is required of matrices bearing certain less frequently used letters. This has necessitated the use of either very long magazine channels, or of two or more magazine channels to contain the large number of 30 matrices bearing the frequently used letters or characters.

In at least one instance, matrices bearing the same characters have been placed in two 35 adjacent magazine channels, and escapement mechanism has been provided in coöperation therewith, whereby when setting up one line of matrices, all of a certain letter, say the letter *e*, will be taken out of the one magazine 40 channel, and then, in setting the next line of matrices, all of the matrices bearing the character *e* will be taken out of the other channel. With such arrangement, it will frequently happen that all or nearly all of the matrices in 45 the one channel will be used up, while there still remains quite a large number of the same letter matrices in the twin or duplicate channels, and that the shift will be made to the nearly or quite empty magazine channel. This con-

dition has hitherto made it necessary to employ, for safety, a larger number of mat-

rices, and hence, longer matrix channels than would otherwise be required.

My present invention, broadly stated, consists in the provision, in connection with the 55 pair or group of magazine channels for matrices bearing the same character, of escapements and escapement actuating mechanism arranged to actuate the several escapements, one at a time, and in a repeating order of succession. With this arrangement where, for instance, the said channels are arranged in pairs, the matrices may be released, one at a time, alternately from the said channels. It therefore follows that the number of matrices 65 in either one of the two channels will never exceed, more than by one, the number in the other channel. Hence, as long as there is a single matrix in either one of the two channels, there will be a matrix available for use 70 when required. This reduces to a minimum the number of matrices and the length of the magazine channels which must be used.

The invention is illustrated in the accompanying drawings, wherein like characters 75 indicate like parts throughout the several views.

Referring to the drawings; Figure 1 is a vertical section taken through the lower portion of a matrix magazine and its support 80 and illustrating my improved escapement mechanism applied thereto. Fig. 2 is a transverse section taken on the line $x^2 x^2$ of Fig. 1. Fig. 3 is a detail view in plan, showing a composite actuating wheel; and Figs. 4, 5 and 6 85 are sections taken respectively on the lines $x^4 x^4$, $x^5 x^5$ and $x^6 x^6$ of Fig. 3.

The matrices 1 are contained in channels 2 of a magazine 3, which magazine, as shown, is supported at its delivery end by a bracket 90 4. The numeral 5 indicates a pawl guiding block that is set into a recess 6 in the upper portion of the bracket 4 and is rigidly secured to said bracket. This guide block 5 has portions that project through recesses in the bottoms of the magazine channels 2. In this illustration, the magazine channels 2 are grouped in pairs with the members of the pairs laterally spaced and adjacent to each other.

Working through suitable longitudinally spaced passages in the bottom of each maga-

zine channel 2, and in the guide block 5, is a pair of endwise movable escapement pawls 7. Each pair of escapement pawls 7 is pivotally connected to a rocker or lever 8 that is intermediately pivoted on a shaft 9 suitably supported by the upper portion of the bracket 4. In the construction illustrated, each of these rockers 8 is provided with a rearwardly projecting arm 10 and with a depending arm 11. A spring 12, shown as secured at its lower end to the supporting bracket 9, engages the depending arm 11 of each rocker 8, and exerts a force tending to hold the said rocker and its escapement pawls 7 in the position shown in Fig. 1.

The two rockers, which coöperate with the two magazine channels containing matrices bearing the same character, are arranged to be alternately oscillated by a pair of cam wheels 13 which, as shown, are rigidly secured to an interposed ratchet wheel 14. The cam wheels 13 have the same number of ratchet-like teeth or cam surfaces (as shown, four), but the teeth of the one cam wheel are set ninety degrees ahead of the teeth of the other cam wheel. The intermediate ratchet wheel 14 is provided with twice as many teeth as the cam wheels 13, being, as shown, eight in number. Each cam wheel 13 operates on the rearwardly extended arm 10 of a rocker 8, and the composite wheel, made up of the said members 13—14—13, are rotatively mounted on a shaft 15 which is suitably supported at its ends by depending lugs 16 of the supporting bracket 4.

For each group of wheels 13—14—13 there is a key-controlled reciprocating actuator which, as illustrated, is in the form of a bar or long driving pawl 17 which is arranged to move endwise through a guide head 18 suitably secured to the supporting bracket 4, and yieldingly pressed forward by a light spring 19 secured to the said guide head. A stop bracket 20 secured to the guide head 18 limits the upward movement of the driving bar or pawl 17. Said driving bar or pawl 17 may be actuated in any suitable way, such, for instance, as by the well known key-controlled power mechanism used in the standard commercial linotype machines.

The operation of the mechanism above described is substantially as follows: When the proper key is depressed, the driving bar or pawl 17 will be forced upward and its upper end will engage with one of the teeth of the ratchet wheel 14, and thereby impart a one-eighth step of rotary movement thereto and to the two cam wheels 13. Such rotary movement of the said cam wheels will cause one or the other thereof to oscillate the rocker 8 in a direction to lower its most forward escapement pawl 7 and raise its rearward escapement pawl 7. This will allow the lowermost matrix 1 to escape from the correspond-

ing channel, and will permit the next succeeding matrix of that channel to lower considerably, but the upwardly moved rear pawl 7 will hold the latter back until it has been engaged by a return movement of the forward escapement pawl produced by passing of the operative tooth or cam surface forward of the free end of the rocker arm 10.

It is thus evident that, under successive steps of movement of the composite wheel 13—14—13, the escapement devices that coöperate with the two adjacent duplicate channels will be operated one after the other, as heretofore more fully set forth.

What I claim is:

1. The combination with a group of matrix channels adapted to contain matrices bearing the same character, of escapement mechanism including a common actuating key arranged to release the matrices, one at a time, first one from one of said channels and then one from another of said channels, in a definite repeating order of succession under repeated key movements, substantially as described.

2. The combination with a pair of matrix channels adapted to contain matrices bearing the same character, of coöperating escapement mechanism arranged to release the matrices, one at a time, first one from one of said channels and then one from the other of said channels in alternate order, substantially as described.

3. The combination with a group of matrix channels adapted to contain matrices bearing the same character, of escapement mechanism comprising pawls, rockers and rocker actuating cam wheels, with the said cam wheels set one in advance of the other, whereby the escapement dogs coöperating with different channels will be operated in a repeating order of succession, substantially as described.

4. The combination with a pair of matrix channels located side by side and adapted to contain matrices bearing the same character, of independent escapement devices for each channel, and means for intermittently and alternately operating said escapement devices, whereby the matrices will be released first one from one of said channels and then one from the other of said channels in alternate order, substantially as described.

5. The combination with a group of matrix channels located side by side, of independent escapement devices for said channels, cam wheels connected for common rotation, each cam wheel operating a different escapement and the said cam wheels being set one in advance of the other, whereby the said escapements will be actuated in succession, and means for imparting intermittent rotary movement to said cam wheels, substantially as described.

6. The combination with a pair of matrix channels adapted to contain matrices bearing the same character, of a rocker, a ratchet-like cam wheel operative thereon, and a pair of escapement pawls operated thereby, a ratchet wheel connected for common intermittent rotary movement with the said two cam wheels, and a vibratory driver inter- 5

mittently operative on said ratchet wheel, substantially as described.

In testimony whereof I affix my signature in presence of two witnesses.

HANS PETERSEN.
